CLAIM

The ornamental design for a seat, as shown and described.

DESCRIPTION

FIG. 1 is a perspective view of a seat in accordance with the new design;

FIG. 2 a front elevational view thereof;

FIG. 3 is a right side elevational view thereof;

FIG. 4 is a left side elevational view thereof;

FIG. 5 is a rear elevational view thereof; and,

FIG. 6 is a top view thereof.

The dashed lines in the drawings illustrate portions of the seat which form no part of the claimed design.
